MAGNETIC WINDOW WASHING APPARATUS

Emory N. Hogensen, Chicago, Ill.

Application February 29, 1952, Serial No. 274,139

6 Claims. (Cl. 15—220)

This invention relates to a window washing apparatus and has particular reference to means for manipulating a pair of window washing pads held on opposite surfaces of a glass window by magnetic force.

It is an object of the present invention to provide window washing pads of the type referred to with thin resilient lip portions that are biased towards the surface of the window being washed and are adapted to fit between the window being washed and the overlapping portion of the adjacent window sash when the windows are moved relative to each other.

Another object of the invention is to provide the window washing pads with cord means for moving them simultaneously without any danger of having the outer pad fall because of the accidental destruction of the magnetic cooperation between the pads.

It is a further object of the invention to provide the cord with readily releasable attaching means by which it may be quickly and easily secured to either end of the pads so that the resilient lips may be faced in the proper direction regardless of whether the top or bottom window is being washed.

Another object of the invention is to provide a handle removably engageable with the top edge of either window sash to facilitate manipulation of the cord by means of which the window washing pads may be moved over the surfaces of the window.

Other objects of the invention and various advantages of the window washing apparatus will be apparent from a consideration of the following detailed description, taken in conjunction with the accompanying drawings showing a preferred illustrative embodiment, in which:

Figure 1 is an elevation of a window with the window washing apparatus embodying the present invention in operative position for the lower window to be washed;

Figure 2 is a detail perspective view of a pair of window washing pads and their holders;

Figure 3 is a cross sectional view showing a pair of window washing pads on opposite surfaces of a window;

Figure 4 is a detail perspective view of the handle showing the cord arrangement for manipulating the window washing pads;

Figure 5 is a cross sectional view showing the window washing apparatus in operative position for the lower window to be washed; and

Figure 6 is a view, similar to Figure 5, showing the window washing apparatus in position for the upper window to be washed.

Referring to the drawings, the reference numeral 2 indicates a conventional window frame having an upper window 3 and a lower window 4 mounted for vertical sliding movement in the frame. When the window is closed the upper edge 5 of the lower window sash and the lower edge 6 of the upper sash are aligned in the same horizontal plane. When either window is moved relative to the other, the space between each window glass and the adjacent surface of the edge 5 or 6 of the other window is rather limited, as indicated at 7, Figure 6.

2

Each pad holder comprises an outer casing 8, an inner casing 9, and a permanent magnet 10. The outer casing consists of a bottom wall 11 and side walls 12 extending at right angles thereto. Although the outer casing is shown as being rectangular, it is obvious that it may be made in any desired shape. The outer casing may be made of any suitable material, but it is preferred to use a suitable plastic. Loops 13 are rigidly secured to two oppositely disposed side walls 12 which become the top and bottom walls of the holder when it is positioned against a window to be washed.

The inner casing 9 is preferably made of the same material as the outer casing 8, and is provided with side walls 14 of slightly less height than the side walls 12. The bottom wall 15 is secured to the inner surface of bottom wall 11 in any suitable manner. A partition wall 14' extends between the side walls 12 and 14 in a plane parallel to the bottom wall 11 and flush with the upper edge of side wall 14. The side walls 12 extend slightly beyond the outer surface of partition wall 14', to form a peripheral flange 12' extending around the open side of casing 8. The magnet 10, which is preferably of U-shape, is embedded in any suitable material 16 capable of holding the magnet with its legs 17 projecting beyond the surface of the holding material which is flush with the side walls 14. The magnet could also be held in place by a wire loop extending around the magnet and through the bottom walls 15 and 11 of the inner and outer casings. The ends of such a wire loop could be secured in any desired manner.

The outer casing 8 is provided with a cover 18 which fits snugly against partition wall 14' and is held within peripheral flange 12' by frictional engagement with said flange to serve as a closure for the open side of the outer casing. The cover 18 has a pair of apertures 19 through which the legs 17 of the magnet extend. The cover 18 comprises part of the window washing pad which also includes a thin resilient metal plate 20 secured to the outer surface of cover 18 and having a lip 21 projecting beyond one edge of the cover. The lip portion 21 is curved outwardly relative to the casing 8 to urge it into close contact with the surface of the window to be cleaned. A piece of sheepskin 22 is adhered to the outer surface of the plate 20 to complete the structure of the pad and to provide a soft durable surface for contacting the surface of the window to be washed. The sheepskin 22 is provided with apertures 23 and the plate 20 is provided with apertures 24, both aligned with apertures 19, to permit legs 17 of the magnet to project therethrough. The exposed ends of legs 17 of the magnet are preferably flush with the outer surface of sheepskin 22 so that the magnet will not interfere with the engagement of the exposed outer surface of sheepskin 22 with the surface of the window to be cleaned.

The handle 25 for facilitating the manipulation of the cord 26 comprises a shank 27 to which one end of a channel shaped member 28 is secured. A roller 29 is transversely mounted in channel 28 adjacent its forward end, and another roller 30 is transversely mounted in the channel just forward of shank 27. An apertured flange 31 is secured within channel 27 rearwardly of roller 29 to guide the cord 26 from roller 29 to roller 30. The rear portion of the bottom wall 32 of channel 28 is bent downwardly at right angles to form a flange 33. A strip 34 of felt or similar material is adhered to the exposed surface of bottom wall 32 and flange 33 so that handle can be positioned on a window sash without scratching it or marring it in any manner. The flange 33 serves as a back gage to hold the handle against the window sash and also provides an open bottom under roller 30 in channel 28 through which cord 26 extends.

The cord 26 has a looped portion 35 of which one end

36 extends around roller 30 and down on the inside of the window to be washed. The other end 37 extends through flange 31 and around roller 29 as well as around roller 30, and drops downwardly on the outside of the window. The ends 36 and 37 each have a simple clasp 38 by means of which they may be detachably secured to loops 13 of casing 8.

The manner of assembling the apparatus varies slightly according to whether the upper or lower window is to be washed. If an upper window is to be washed, the clasps 38 are each secured to the loops 13 at one side of the casing 8. A suitable detergent is applied to each pad and the pads are then applied to each casing with the lip portions 21 extending downwardly. The casings 8 are arranged so that the opposite poles of each magnet 10 are aligned when the casings are juxtaposed in face to face relationship. The upper window is then lowered a short distance and the casing to which the end 37 of cord 26 is secured is positioned outside the window with its sheepskin 22 held against the surface of the window by manual pressure. The other casing is then positioned on the inside of the window with its pad 22 held against the inside surface of the window. The pads are then moved manually until they are in alignment, at which time the magnetic force holds them against separation and the manual pressure may be removed from each casing. The handle 25 is then positioned on the upper edge 39 of the upper window sash.

In washing the window, the handle 25 is preferably held against the upper edge of the sash by one hand while the cord 26 is manipulated with the other. The pads are pulled upwardly in close contact with the glass by means of loop 35. A simple downward pull on loop 35 will pull both casings upwardly and the magnetic force of magnets 10 holds the pads against the window. When the pulling force on loop 35 is released the force of gravity will pull the casings back to the lower edge of the window. As shown in Figure 6, the casing 8 is too wide to pass through space 7. The lip 21 will pass through this space and reach the edge of sash 6 so that the entire surface of the window may be washed. After the pads have been moved vertically to cover one portion of the window the handle 25 is moved transversely so that the next vertical movement of the pads will cover a different portion of the window. In this manner the entire surface area of the window may be washed. When the detergent has been applied over both sides of the window the apparatus is removed and the detergent is allowed to dry. Both sheepskin pads 22 are removed from the casings 8 and are replaced by clean dry pads of the same type. The apparatus is then applied to the window in the same manner as previously described, and the detergent is wiped off both surfaces by the window simultaneously by a repetition of the washing operation.

If the lower window is to be washed the end 37 of cord 26 must be dropped over the upper edge of sash 5 and through the space 7 before it is attached to loop 13. The pads are secured to each casing with the lip 21 extending upwardly and both pads may be positioned on opposite sides of the window by magnetic force before the cord is secured to loop 13. The lower window 4 must be raised to permit the casing 8 to be placed on the outside of the window. After the ends of cord 26 have been secured to loops 13 the washing operation is the same as previously described.

Although I have described a preferred embodiment of my invention in considerable detail, it will be understood that the description thereof is intended to be illustrative, rather than restrictive, as many details may be modified or changed without departing from the spirit or scope of the invention. Accordingly, I do not desire to be restricted to the exact details of construction described.

I claim:

1. A window washing apparatus comprising a pair of casings, a pad detachably secured to each of said casings,

a magnet rigidly secured in each casing whereby said casings and pads may be retained on opposite surfaces of a window by magnetic force, a cord having its opposite ends each secured to one of said casings, and a handle having a pair of rollers mounted in said handle, the cord secured to one of said casings extending over both of said rollers, the cord secured to said other casing extending over one roller only, both portions of said cord extending downwardly from said one roller in a loop, said looped portion of said cord being disposed on the inside of the window whereby said cord may be pulled to move said pads over both surfaces of the window simultaneously.

2. A window washing apparatus comprising a pair of casings, a pad detachably secured to each of said casings, a magnet rigidly secured in each casing whereby said casings and pads may be retained on opposite surfaces of a window by magnetic force, a cord having its opposite ends each secured to one of said casings, and a handle having a pair of longitudinally spaced rollers mounted transversely for rotation in said handle, said handle having a flange to facilitate holding it against the upper sash of the window to be washed and an open bottom portion under one of said rollers, the cord secured to one of said casings extending over both of said rollers, the cord secured to said other casing extending over said one roller only, both portions of said cord extending over said one roller dropping through said open bottom portion in a loop, whereby the looped portion of said cord may be pulled to move both of said pads upwardly along opposite surfaces of the window simultaneously, the weight of said pads and casings being sufficient to cause them to move downwardly by gravity when the pulling force is removed from the looped portion of the cord.

3. A window washing apparatus comprising a pair of casings, a pad detachably secured to each of said casings, each of said pads having a thin resilient lip extending beyond one edge of its casing, said lip being curved outwardly whereby its resilience urges it into close contact with the window against which it is positioned, a magnet rigidly secured in each casing whereby said casings and pads may be retained on opposite surfaces of a window by magnetic force, a cord having its opposite ends each secured to one of said casings, and a handle having a pair of longitudinally spaced rollers mounted transversely for rotation in said handle, said handle having a flange to facilitate holding it against the upper sash of the window to be washed and an open bottom portion under one of said rollers, the cord secured to one of said casings extending over both of said rollers, the cord secured to said other casing extending over said one roller only, both portions of said cord extending over said one roller dropping through said open bottom portion in a loop, whereby the looped portion of said cord may be pulled to move both of said pads upwardly along opposite surfaces of the window simultaneously, the weight of said pads and casings being sufficient to cause them to move downwardly by gravity when the pulling force is removed from the looped portion of the cord.

4. In an apparatus for washing windows mounted in a conventional window frame having a pair of windows slideable vertically relative to each other, a pair of casings each having a magnet rigidly secured therein whereby said casings may be retained on opposite surfaces of a window by magnetic force, and a pad detachably secured to each of said casings, each of said pads having a thin resilient lip extending beyond one edge of its casing, said lip being curved outwardly relative to its casing whereby its resiliency urges it into close contact with said window.

5. In an apparatus for washing windows mounted in a conventional window frame having a pair of windows slideable vertically relative to each other, a pair of casings each having a magnet rigidly secured therein whereby said casings may be retained on opposite surfaces of a window by magnetic force, a pad detachably secured to

each of said casings, each of said pads having a lip extending vertically beyond one edge of its casing, each of said lips being thin enough to pass between a window and the sash of the adjacent window, a loop secured to opposite edges of each of said casings, a handle adapted to be held against the upper sash of the window to be washed, a pair of rollers mounted in said handle, a cord extending over said rollers and having its end portions extending on opposite sides of the window to be washed, and a clamp on each end portion of said cord releasably engageable with either of said loops whereby said casings may be secured to said cord with said lips extending towards the closest sash of the adjacent window, said cord being operable to move both of said casings and pads while they are retained on opposite surfaces of the window by said magnets.

6. In a window washing apparatus, a casing having one open side, a U-shaped magnet rigidly secured within said casing with its legs projecting through said open side, and a pad, said pad including a cover fitting said casing and serving as a closure for said open side, a thin metal plate secured to the outer surface of said cover and hav-

ing a lip extending beyond one edge thereof, and a layer of soft material secured to the outer surface of said thin metal plate, said cover, metal plate and soft layer each being apertured to permit the legs of said magnet to project therethrough, the outer ends of said legs being substantially flush with the outer surface of said layer of soft material.
